[57] CLAIM

The ornamental design for a combined drinking cup and holder, as shown and described.

DESCRIPTION

FIG. 1 is a perspective view of a combined drinking cup and holder showing our new design;

FIG. 2 is a front elevational view thereof;

FIG. 3 is a bottom plan view thereof and;

FIG. 4 is a top plan view thereof.

The left side elevational, right side elevational and rear elevational views of the combined drinking cup and holder shown in FIG. 1 are identical to the front elevational view shown in FIG. 2.
